UNITED STATES PATENT OFFICE.

HENRY F. SCHWARZ, OF NEW YORK, N. Y., ASSIGNOR TO NATIONAL ECONOMIC PLANS, INC., OF NEW YORK, N. Y., A CORPORATION OF NEW YORK.

DESIGN FOR A COUPON.

Application filed February 23, 1926. Serial No. 16,646. Term of patent 7 years.

To all whom it may concern:

Be it known that I, HENRY F. SCHWARZ, a citizen of the United States, residing at New York city, in the county and State of New York, have invented a new, original, and ornamental Design for Coupons, of which the following is a specification, reference being had to the accompanying drawing, forming part thereof.

The figure is a plan view of a coupon, showing my new design.

I claim:

The ornamental design for a coupon, as shown.

HENRY F. SCHWARZ.
